CONDIMENT DISPENSER

Marinos C. Caglagis, Fort Worth, Tex.

Application October 7, 1949, Serial No. 5,352

Term of patent 3½ years

(Cl. D44—22)

To all whom it may concern:

Be it known that I, Marinos C. Caglagis, a citizen of the United States of America, residing at Fort Worth, in the county of Tarrant and State of Texas, have invented a new, original, and ornamental Design for a Condiment Dispenser, of which the following is a specification, reference being had to the accompanying drawing, forming part thereof.

I claim:

The ornamental design for a condiment dispenser, substantially as shown.

MARINOS C. CAGLAGIS.
